UNITED STATES PATENT OFFICE.

THOMAS F. HUGHES, OF PAWTUCKET, RHODE ISLAND, ASSIGNOR TO UNITED WIRE AND SUPPLY COMPANY, OF AUBURN, RHODE ISLAND, A CORPORATION OF RHODE ISLAND.

MEANS FOR MOLDING A FIN INTO A CASTING.

Application filed May 28, 1924. Serial No. 716,376.

The object of this invention is to provide means and also a method of applying a heat-protecting strip of metal or material of relatively-high heat-resisting qualities to the edge of a strip or sheet of metal having relatively lower heat-resisting qualities and molding a casting about the protected or inclosed edge of the strip or sheet.

With these and other objects in view, the invention consists of certain novel features of construction, as will be more fully described, and particularly pointed out in the appended claims.

In the accompanying drawings:

15. Figure 1 is a perspective view illustrating a channel-shaped strip of high-heat-resisting material as applied to the edge of a strip or sheet of relatively-low-heat-resisting material.

20. Figure 2 is a detail showing a length of the channel-shaped strip.

Figure 3 is a perspective view showing a length of the strip or sheet of relatively-low-heat-resisting material.

25. Figure 4 is a view showing deeply-corrugated rolls for roughening the inner surfaces of the channel-shaped strip and forcing these surfaces into the corresponding surfaces of the relatively-soft metal.

30. Figure 5 is an enlarged sectional elevation illustrating the roughened, inner surfaces of the side walls of the channel-shaped strip as imbedded into the corresponding indentations in the surfaces of a relatively softer metal.

35. Figure 6 is a sectional view which shows a portion of a cylinder into the outer surface of which is molded the protecting edges of the heat-radiating fins.

40. It is found in practice of advantage to mold a plurality of strips or fins of heat-radiating material edgewise and in spaced apart relation about the outer surface of a so-called air-cooled cylinder of an internal combustion engine, for the purpose of cooling the same by radiating the heat therefrom, and it is found that thin strips of copper perform this radiating action to the best advantage, but as copper is a relatively

45. low heat resisting material, unless it is protected, it will melt when cast iron is poured about its edge. Therefore, in order to protect the supporting edges of the fins against the excessive heat of the molten metal, I in-

case or cover these edges of the fins in a 55 channeled member of relatively high heat resisting materials which protects the copper and prevents it from melting upon being mounted into the casting.

Further, in some instances, in order to 60 firmly secure the channel-shaped member to the edge of the copper, I corrugate or otherwise roughen the inner surface of the side walls of the channel and force these roughened surfaces into the softer metal by pressure, while in still other cases before I apply the channel strip to the edge of the copper, I insert a strip of soldering metal into the channel member and when the cast metal is molded about the incasing edge of the fin 65 70 this solder which is of a low melting quality solders the copper to the channeled member thus firmly securing the fin in the casting; and the following is a detailed description of the present embodiment of my 75 invention:—

With reference to the drawings, 10 designates the strip of sheet copper which may be prepared for use as a heat-radiating fin for a so-called air-cooled cylinder and as 80 it is impractical to mold the edge of this strip of copper directly into the outer surface of the cylinder 11, it has been found of advantage to incase or insert the edge of the copper, which has to be molded into 85 the cylinder, in a protecting material and to perform this protecting function I preferably employ a strip of steel and form the same into channel shape as at 12, the side walls 13 and 14 of this strip being spaced 90 to just receive the edge of the copper strip between them and in order to firmly secure this channel strip to the edge of the copper, I, in some cases, first position the copper strip into the channel and then pass this 95 covered edge through a set of knurling or corrugating rolls 15 which serve to indent or roughen the side walls of the channel member both on their outer faces and also on the inner faces, the roughened or corrugated inner face being forced into the correspondingly shaped surface of the softer metal 10 thereby securely locking the two metals together, the outer roughened surface also serving to receive the molten metal 100 105 and securely locking the fin in the cylinder.

In other cases, instead of passing this protected or steel covered edge of the copper

through the rolls 15, in order to force and lock the channel member onto the copper, I insert a strip of soldering metal as at 16 into the channel member before the edge of the copper is positioned therein and then upon subjecting this edge to the heat of the molten metal of the casting, this strip of solder is fused and solders and so locks the copper to the steel and as the steel is held firmly in the cast metal the whole is locked together without the necessity of corrugating or roughening the surfaces of the channel member in order to lock the same to the copper.

15 I do not wish to be restricted to the applying of these channeled members to heat-radiating fins as the same may be applied to the edges of sheet copper to be used for any other purpose.

20 Having thus described one illustrative embodiment of my invention and the best mode known to me for carrying out my method, I desire it to be understood that although specific terms are employed, they 25 are used in a generic and descriptive sense and not for the purpose of limitation, the scope of the invention being defined and limited only by the terms of the appended claims.

30 I claim:

1. A heat-radiating fin adapted to be positioned in a metal casting comprising a metal strip, and a protecting member attached along the edge thereof of a material 35 having a relatively higher fusing point than the metal strip.

2. A heat-radiating fin adapted to be positioned in a metal casting comprising a metal strip and a protecting member at-

tached along each side thereof adjacent its 40 edge of a material having a relatively higher fusing point than the metal strip.

3. A heat-radiating fin adapted to be positioned in a metal casting comprising a metal strip and a protecting member 45 attached to the edge and each side of the strip adjacent thereto of a material having a relatively higher fusing point than the metal strip.

4. A heat-radiating fin adapted to be positioned in a metal casting comprising a metal strip, a channel-shaped heat protecting member of a relatively high fusing point, attached to its edge, said member being of a material having a relatively 55 higher fusing point than said metal strip or casting.

5. A heat-radiating fin adapted to be positioned in a metal casting comprising a metal strip, a channel-shaped heat protecting member attached to the edge of said strip, said member being of a material having a relatively higher fusing point than said metal strip or casting and having a rough inner surface forced into friction engagement with said strip. 65

6. A heat-radiating fin adapted to be positioned in a metal casting comprising a metal strip, a channel-shaped heat protecting member of a relatively high fusing 70 point attached to its edge, said member being of a material having a relatively higher fusing point than said metal strip or casting and having rough inner and outer surfaces for friction engagement with 75 said strip and casting.

In testimony whereof I affix my signature.

THOMAS F. HUGHES.
